UNITED STATES PATENT OFFICE.

JOSEPH NISENSON, OF BROOKLYN, NEW YORK, ASSIGNOR TO EAGLE METALLIC BED CORPORATION, OF BROOKLYN, NEW YORK, A CORPORATION OF NEW YORK.

DESIGN FOR A BED END OR SIMILAR ARTICLE.

Application filed April 3, 1929. Serial No. 30,743. Term of patent 7 years.

To all whom it may concern:

Be it known that I, JOSEPH NISENSON, a citizen of the United States of America, residing at Brooklyn, county of Kings, city and State of New York, have invented a new, original, and ornamental Design for a Bed End or Similar Article, of which the following is a specification, reference being had to the accompanying drawing, forming part hereof, in which—

Figure 1 is a perspective view of a bed-end having my new design and Figure 2 is a top plan view thereof.

I claim:

The ornamental design for a bed-end or similar article as shown.

Signed at New York city, New York, this 1st day of April, 1929.

JOSEPH NISENSON.
